US0D1028910S

(12) **United States Design Patent** (10) **Patent No.:** **US D1,028,910 S**
(45) **Date of Patent:** **** May 28, 2024**

(54) **CONTROL DEVICE WITH ICONS**

(71) **Applicant:** **Lutron Technology Company LLC**,
Coopersburg, PA (US)

(72) **Inventors:** **Gregory S. Altonen**, Easton, PA (US);
Jason C. Killo, Emmaus, PA (US);
Brad M. Kreschollek, Bethlehem, PA
(US); **Madia L. Rivera**, Bethlehem, PA
(US)

(73) **Assignee:** **Lutron Technology Company LLC**,
Coopersburg, PA (US)

(**) **Term:** **15 Years**

(21) **Appl. No.:** **29/860,135**

(22) **Filed:** **Nov. 16, 2022**

Related U.S. Application Data

(63) Continuation of application No. 29/824,826, filed on Jan. 27, 2022, now Pat. No. Des. 971,859, which is a continuation of application No. 29/771,118, filed on Feb. 19, 2021, now Pat. No. Des. 945,382, which is a continuation of application No. 29/688,169, filed on Apr. 18, 2019, now Pat. No. Des. 913,252, which is a continuation of application No. 29/633,659, filed on Jan. 15, 2018, now Pat. No. Des. 846,507.

(57) **CLAIM**

The ornamental design for a control device with icons, as shown and described.

DESCRIPTION

FIG. 1 is a front view of a control device with icons showing our new design;

FIG. 2 is a left side view thereof;

FIG. 3 is a right side view thereof;

FIG. 4 is a top view thereof; and,

FIG. 5 is a bottom view thereof.

The rear view forms no part of the claimed design and is omitted.

The uniform dashed broken lines illustrate structure or features which form no part of the claimed design; the broken lines themselves form no part of the claimed design.

1 Claim, 3 Drawing Sheets
